WILLIAM E. MOORE, OF CHICAGO, ILLINOIS, ASSIGNOR TO ANGUS HENDERSON, OF CHICAGO, ILLINOIS.

MACHINE FOR MOLDING AND BAKING CONTAINERS FOR ICE-CREAM AND THE LIKE.

1,245,008.

Specification of Letters Patent. Patented Oct. 30, 1917.

Application filed March 27, 1915, Serial No. 17,436. Renewed June 4, 1917. Serial No. 172,810.

To all whom it may concern:

Be it known that I, WILLIAM E. MOORE, a citizen of the United States, and a resident of Chicago, county of Cook, and State of Illinois, have invented a certain new and useful Improvement in Machines for Molding and Baking Containers for Ice-Cream and the like, of which the following is a full, clear, and exact specification.

10 This invention relates to a class of apparatus adapted to be used for producing cups made of pastry.

My invention has for its object primarily to provide a machine for molding and baking forms of containers, or cups from a batter of rice flour, or other cereals, or any suitable ingredients for permitting ice cream, custards, and like condiments to be conveniently and temptingly dispensed at pleasure places and elsewhere, whereby the container may be eaten by a person together with the consumption of its contents. The invention consists essentially of a hollow cylindrical base which is supported on standards at a suitable elevation and the top of the base is provided with a stationary transverse plate having one or a number of spaced tapered passages therethrough serving as the female members of a like 20 number of molds for forming the containers. Within the cylindrical base is a transverse freely movable support or plate adapted to be raised and lowered to and from the lower open ends of the female members of the 25 molds, and projecting upwardly at spaced intervals from the movable plate are a number of plungers adapted to force the containers when made outwardly of the female members. One of the plungers is reciprocably disposed in each of the female members of the molds, and each plunger has on its upper end a head of a size to adapt it to close the lower end of its respective female member of the mold when seated therein.

40 Above the hollow base is a carrier, or bracket adapted to be adjustably moved to and from the stationary plate of the base, and projecting from the bracket are the male members of the molds for forming the containers. The male members correspond in shapes, but are somewhat smaller than the female members, and each male member is arranged so as to removably interfit the

complemental female member when the bracket is adjusted accordingly with relation to the base. 55

Other objects of the invention are to provide operative means in the hollow base whereby the plungers may be reciprocably directed inwardly and outwardly of the female members of the molds, and which also serves for adjusting the bracket relatively to the base so that the male members of the mold will be guided interiorly and outwardly of the female members simultaneously with the alternate movement of the plungers; to provide a brake mechanism in conjunction with the operative means to allow the male members to be held against movement when forced home in the female members during the molding of the containers; to provide a hopper whereby a suitable quantity of the material for making the containers may be fed into the molds; to provide an electric circuit; to provide in the circuit one or a number of resisting coils arranged in contact with the molds so as to be heated for baking the material of the containers; and to provide in the circuit a rheostat for permitting the supply of current to the resisting coils to be regulated. 60

With these and other objects in view, the invention will be hereinafter more particularly described with reference to the accompanying drawings forming a part of this specification in which similar characters of reference indicate corresponding parts in all the views, and will then be pointed out in the claims at the end of the description. 85

In the drawings, Figure 1 is a longitudinal vertical section, partly in detail, of one form of machine for molding and baking containers embodying my invention, taken on the line I—I of Fig. 2. 90

Fig. 2 is a top plan of the machine. 95

Fig. 3 is a sectional view, partly in detail taken on the line III—III of Fig. 1.

Fig. 4 is an enlarged sectional view taken on the lines IV—IV of Fig. 2.

Fig. 5 is an enlarged fragmentary sectional view taken on the line V—V of Fig. 2. 100

Fig. 6 is an enlarged fragmentary sectional view, showing the members of one of the molds in position for making and baking a container, and

Fig. 7 is a diagrammatic view of the elec-

tric circuit, and a sectional view through one of the tubular uprights of the carrier of the machine.

The machine for molding and baking containers for ice cream and the like has a hollow base 10 which is preferably cylindrical in shape, and this base is supported on a number of standards, as 11, at a suitable elevation. Transversely of the top of the base 10 is a stationary metal plate 12 having one or a plurality of spaced passages 13 vertically therethrough, and these passages taper toward the lower ends thereof. The passages 13 serve as the female members of molds, as 14 Fig. 6, for forming the containers, as 15, which are preferably cup-shaped with a flat bottom, as shown, whereby the container will rest without danger of falling over when placed on a flat support.

Interiorly of the hollow base 10 is a transverse freely movable support, or plate 16 adapted to be raised and lowered to and from the lower open ends of the female members, and projecting upwardly at spaced intervals from the movable plate are a number of plungers 17, all of which are similarly formed. The plungers 17 correspond in numbers to the female members 13, and each plunger is disposed in one of the female members. Each of the plungers 17 has a post and a head 19 on its upper end. The head 19 of each of the plungers is in the form of a disk of a size adapted to close the lower end of the female member in which it is disposed when the plungers are moved accordingly, and the top surface of each head may be slightly concaved, as at 20. When the supporting plate 16 is moved upwardly it contacts with the underside of the stationary plate 12 of the base 10 so that the plungers will pass upwardly into the female members of the molds for forcing the containers when molded and baked outwardly of the top of the female members so as to be conveniently removed from the machine, as will be hereinafter more fully explained, and when the supporting plate is directed downwardly so that the heads 19 of the plungers are seated in the lower ends of the female members this movement of the supporting plate is checked by contact with an annular flanged plate, or ring, as 21, which is rigidly held in the hollow base 10 in spaced relation to the stationary plate 12.

Above the base 10 and adjustably movable to and from the stationary plate 12 is a coöperating carrier, or bracket 22. The bracket 22 has a longitudinally disposed plate 23 through which are a number of threaded openings in register with the female members 13 of the base 10, and in these openings are screwed the exteriorly threaded open end parts of the hollow metal male members 24 of the molds. The lower closed

ends of the male members 24 extend downwardly from the underside of the plate 23 so as to interfit the complementary female members when the bracket 22 is lowered on the base 10, and these lower ends of the members are tapered, as shown, to conform with the shapes of the female members. The tapered ends of the male members are smaller in sizes than the female members to provide a slight space between the members of each mold for receiving the material of which the containers are made. In order that the plate 23 of the bracket 22 and the male members 24 may be accurately adjusted to and from the base as well as the female members 13, in openings through this plate of the bracket are held the upper ends of a number of tubular uprights or pipes, as 25. I prefer to employ three of the tubular uprights 25, and these uprights are triangularly arranged in spaced relation. The lower end portions of the tubular uprights 25 are movably disposed through openings in the stationary plate of the base 10, and the lower ends of the uprights are connected to the upper ends of a spider, as 26, arranged within the base 10 so as to be moved upwardly and downwardly through the ring 21 for adjusting the bracket 22 with respect to the base. The spider 26 is preferably formed with three triangularly disposed arms 27, 27^a, 27^b which converge downwardly in approximately a cone-shape, and extending downwardly from the apex of these arms is a short post 28. When the carrier, or bracket 22 and the male members 24 are elevated above the base 10, as shown in Fig. 1, the movable plate of the plungers 17 normally rests on the upper ends of the spider 26, and serving as means whereby the plungers may be reciprocably directed inwardly and outwardly of the female members of the mold as well as serving to adjust the bracket 22 for guiding the male members 24 interiorly and outwardly of the female members 13 of the molds simultaneously with the alternate movement of the plungers, in the base 10 is provided a manually operative lever, as 29.

The lever 29 is preferably in the form of a bar having one of its ends slotted, at 30, and this slotted end of the lever is pivoted, at 31, to the lower end of the post 28 of the spider 26. The lever 29 extends through a vertically disposed slot 32 in the wall of the hollow base, the lever being of a length so as to project some distance outwardly of the base, and the outer end of this lever terminates with a handle 33 whereby the lever may be conveniently raised, or lowered. The lever 29 is arranged so that its central part is adjacent to the slot 32 of the hollow base, and this part of the lever is rotatable on a shaft 34 held in the wall of the base 10. When the handle of the lever 29 is directed

downwardly its slotted end 30 and the spider 26 will be swung upwardly in the base. The tubular uprights 25 of the carrier or bracket 22 together with the plate 23 and the male members 24 of the molds will then be likewise guided upwardly, as shown in Fig. 1, and during the upward movement of the spider it will contact with the underside of the movable supporting plate 16 which in 5 turn will be directed upwardly for guiding the plungers also upwardly in the female members 13 of the molds, the stationary plate 12 of the base 10 being contacted with by the supporting plate 16 to limit its movement. By guiding the handle 33 of the lever 29 in an upward direction, as indicated at 35 Fig. 1, the slotted end of the lever 29, the spider 26, the uprights 25, the plate 23 and the male members 24 of the molds will 10 be reversely moved for the male members to be guided into the female members of the molds. As the movable supporting plate 16 of the plungers 17 is made comparatively heavy in weight it will be automatically 15 lowered with the descent of the spider 26, and the plungers will likewise descend in the female members of the molds. The supporting plate 16 will move upon the flanged ring 21 of the base 10 when the heads 19 of 20 the plungers 17 have been seated in the lower ends of the female members of the molds, as shown in Fig. 6, and the lowering of this plate together with the plungers will thereby be stopped by the flanged ring for the 25 heads 19 of the plungers to serve as the bottoms of the female members of the molds. By swinging the handle of the lever 29 a sufficient distance upwardly the spider 26 and the bracket 22 will be lowered sufficiently 30 for the male members 24 to be seated in the female member 13, and serving to hold the male members against movement when forced home during the molding of the containers, on the lever 29 is provided a 35 brake mechanism, as 36.

The brake mechanism 36 has a ratchet toothed wheel 37 held on the shaft 34 of the lever 29, and pivoted to the lever is a pawl 38 adapted to be swung into and out of engagement with the ratchet wheel. To the pawl 38 is connected one end of a rod 39 having its other end pivoted to a substantially L-shaped lever 40 having the central part of its upwardly projecting arm pivoted, 50 at 41, to the lever 29 adjacent to its handle 33. The second arm of the lever 40 is disposed in spaced parallel relation to the handle 33, and by forcing this second arm of the lever 40 toward the handle of the lever 29 the pawl 38 will be caused to engage one of the teeth of the ratchet wheel 37. When the second arm of the lever 40 is moved away from the handle of the lever 29 the pawl 38 will be released from engagement 55 with the ratchet wheel 37, and the lever 29

may then be swung either upwardly or downwardly on the shaft 34. After the handle part of the lever 29 is swung downwardly to its maximum distance for elevating the bracket 22 and the male members 24 70 of the molds as well as raising the plate 16 and the plungers 17 these parts will be held against movement by applying the brake mechanism, as explained. After these parts are reversely adjusted with respect to the 75 base 10 by first releasing the brake mechanism and then swinging the lever 29 upwardly so that the male members 24 of the mold interfit in the female members the brake mechanism 36 of the lever is applied, 80 and the parts will again be held against movement.

The containers 15 may be made of a batter of rice flour, or other cereals, or any suitable ingredients of an edible character, and 85 serving to permit the batter to be conveniently fed into a number or all of the female members of the molds at the same time, I provide a hopper, as 42. The hopper 42 is formed of a receptacle 43 of an irregular 90 curved shape, as indicated in Fig. 2, so as to be adapted to be passed between the uprights 25 of the carrier, or bracket 22 for being disposed over the female members 13 of the base 10. The top of the receptacle 43 95 is open, while through its bottom 44 are a number of spaced openings in each of which is a short tube, or outlet, as 45, and these tubes are arranged so as to be registered with the female members 13 of the molds when 100 the receptacle is accordingly guided over the top of the base 10. Interiorly of the receptacle 43 is a plate 46 which is freely movable upwardly and downwardly in the receptacle, and provided on the underside of this 105 movable plate are a number of spaced circular disks, or stoppers 47 the lower edges of the peripheries of which taper toward the centers thereof. The diameters of these disks are somewhat larger than the openings 110 in the bottom of the receptacle, while the tapered parts thereof are smaller than the openings so as to be seated therein. The stoppers 47 are arranged on the plate 46 so that each will close one of the openings in 115 the bottom of the receptacle 43, and through this movable plate may be one or a number of openings, or outlets 48. The plate 46 is of a weight so that it will be normally disposed at the bottom of the interior of the receptacle for the disks 47 to close the passages through the openings and through the tubes 45 of the bottom 44. The receptacle 43 is hingedly mounted to the machine by a bracket, as 49, projecting latterly from its 120 wall, and on the free end of this bracket are two apertured lugs rotatably disposed on a post 50 extending upwardly from part of the stationary plate 12 of the base 10 so that the hopper may be swung to and from a position 125

over the base for registering the tubes 45 of the receptacle 43 with the female members 13 of the molds. As shown at 51 in Fig. 2, when the hopper is disposed over the base 10 for registering the tubes 45 with the female members of the molds two of the female members, as 13^a and 13^b, will not be directly under the receptacle 43, and to allow the batter to be fed from the hopper into these members simultaneously with the delivery of the batter to the other members, in spaced passages through parts of the receptacle are two tubes 45^a and 45^b. The passages of the feed tubes 45^a and 45^b are angularly disposed through the bottom of the receptacle and through its wall so that these tubes will extend laterally from the receptacle for being disposed over the female member 13^a and 13^b when the hopper is in position for permitting the batter to be fed to the female members, and these passages are adapted to be also closed by stoppers 47^a provided on the underside of the movable plate 46, the stoppers 47^a being similarly formed to the stoppers 47. To supply at intervals the female members of the molds with suitable quantities of the batter material for making the containers a quantity of the batter is delivered into the receptacle 13 on top of the plate 46, and the hopper is swung over the base 10 to register the outlet tubes of the receptacle with the female members of the molds following the elevation of the bracket 22, the male members 24, the plate 16 and the plungers 17, as above described. To permit the plate 46 and the stoppers 47, 47^a to be raised in the receptacle for the batter to flow through the outlets 48 of the plate 46 and through the tubes of the bottom of the receptacle, to an eye 52 extending upwardly from the center of the plate 46 is fastened one end of a line 53 disposed over a pulley 54 held on a bar 55 provided across the open top of the receptacle of the hopper, and this line is passed through a hole in the upper part of the wall of the receptacle. The opposite end of the line 53 is attached to the upper end of the vertical arm of a substantially L-shaped hand-lever 56 which is pivoted, at 57, to the receptacle so that its longitudinal arm will extend laterally from the wall of the receptacle. By swinging this hand-lever downwardly its vertical arm will be directed from the receptacle, and the line 53 will be guided over the pulley 54 to raise the plate 46 and the stoppers a distance in the receptacle for the batter of the containers to be fed through the outlet tubes of the receptacle into the female members of the molds. When the required quantity of the batter has been delivered to the female members the hand-lever 56 is released, and the plate 46 will be lowered in the receptacle 43 by its own weight for its stoppers to close

the outlets in the bottom of the receptacle. 65 The delivery of the batter to the female members of the molds will thereby be shut-off, and the hopper is swung from its position over the base 10 in a lateral direction from the machine. The male members 24 70 of the molds are then caused to be inserted in the female members by directing the lever 29 upwardly, as hereinbefore explained, and by exercising sufficient leverage on this lever the male members may be driven home in the 75 female members for properly forming the containers 15 into cup-shapes having flat bottoms, as shown in Fig. 6, to receive ice cream, custards, and like condiments for being dispensed. When the containers are being formed by the coöperation of the members of the molds in this manner, a quantity of the batter will likely be caused to flow over the upper edges of the female members, and to trim these surplus parts of the 80 batter from the upper edges of the containers, projecting from the exterior of the wall of each of the male members 24 at the juncture thereof with the plate 23 of the bracket 22 is an annular cutter, as 58. The cutters 85 58 are arranged so that when the male members are forced home in the female members during the forming of the containers they will contact with and cut through the batter circumferentially for freeing the upper 90 edges of the containers of all the surplus material. 95

In order to effectually and quickly bake the batter of the containers when molded, I provide an electric circuit 59 leading from 100 a suitable source of electricity supply, for instance a battery, as 60, and the circuit also leads to a plural series of connected resisting coils 61 and 62. The series of the resisting coils 61 are arranged so that each 105 coil is wound spirally of the exterior of each of the female members 13 of the molds, and these coils are embedded in layers, as 63, of fire clay or other electricity resisting material one of which is applied on the wall 110 of each of the female members. The series of the resisting coils 62 are arranged so that each coil is embedded in a core, as 64, also of fire clay, or other electricity resisting material, and one of these cores is provided in the hollow part of each of the male members of the molds. The current is transmitted to the connected series of resisting coils 61 in the male members 24 of the molds by a wire 65 leading from one pole of the battery 60 to the last coil of the series, this wire being disposed if desired through one of the tubular uprights 25 of the carrier, or bracket 22, and from the second pole of the battery is a wire 66 leading to the first 115 120 coil in the series of the connected resisting coils 61. The current is also synchronously transmitted to the connected series of re-

sisting coils 62 of the female members 18 of the molds by a wire 67 leading from the last coil of the series to the wire 65, and from the first coil of this connected series is a 5 wire 68 leading to the switch, as 69, of a rheostat 70 which is interposed in the wire 66, part of this wire being connected to the contacts of the rheostat, while the other part of the wire is connected to the switch 69. 10 The rheostat 70 may be of any suitable type adapted to permit the supply of current to the resisting coils to be regulated whereby the containers may be properly baked by the heat generated by the coils and transmitted to the molds, and this rheostat also 15 being of a form to permit the supply current to the coils to be cut-off by throwing the switch 69 free of all engagement with the contacts of the rheostat, as indicated, at 20 71, Figs. 1 and 7. To turn-on the current for heating the molds the switch 69 is swung into engagement with one of the contacts of the rheostat. The circuit will then be transmitted from the battery over the wire 25 65, through the plural series of connected resisting coils 61, and from the battery over the first part of the wire 66, through the rheostat 70 and its switch 69, thence over the second part of the wire 66 to the series 30 of coils 61. The male members of the mold will thereby be heated, and simultaneously therewith the current will be transmitted from the wire 65, over the wire 67, to and through the plural series of connected resisting coils 62. The current will also be 35 transmitted from the switch 69, over the wire 68 to the series of coils 62, and by adjusting the switch of the rheostat accordingly into engagement with the various contacts of the rheostat the supply of the current from the battery may be effectually controlled for heating the molds to any desired degree. When the containers, or cups 40 are formed and baked in this manner, the lever 29 is swung downwardly for elevating the bracket 22 and the male members of the molds above the base 10 as well as for guiding the plate 16 and the plungers 17 upwardly, as above explained, and the baked 45 containers will then be forced outwardly of the female members for removal from the machine so as to be used for dispensing ice cream, frozen ices, custards, and other condiments of this class. 50

55 In the foregoing description, I have embodied the preferred form of my invention, but I do not wish to be understood as limiting myself thereto, as I am aware that modifications may be made therein without departing from the principle, or sacrificing any of the advantages of this invention; therefore I reserve to myself the right to make such changes as fairly fall within the scope of the appended claims.

Having thus described my invention, I 65 claim as new and desire to secure by Letters Patent:—

1. In a machine of the character described, a hollow base having a stationary transverse top plate provided with a vertically disposed passage therethrough serving as the female member of a mold for making a container of edible material, a movable support in the base, a plunger held on the support, and reciprocably disposed through the lower 70 end of the female member, said plunger being formed to provide a movable bottom for the female member when lowered so that its free end rests in the lower open end of the female member, a carrier adapted to be 75 raised and lowered to and from the top plate of the base, a male member on the carrier, adapted to be guided inwardly and outwardly of the female member when the carrier is accordingly moved, and the male 80 member being smaller in size than the interior of the female member for forming the interior of the container, and means in the base, connected to the carrier and adapted to contact with the support of the plunger, 85 whereby the carrier and the male member will be raised and lowered relative to the base for alternately inserting and withdrawing the male member in and out of the female member as well as synchronously reciprocating the plunger in the female member 90 when the said means is operated, substantially as set forth and for the purpose specified. 95

2. In a machine of the character described, 100 a hollow base having a stationary transverse top plate provided with a plurality of vertically disposed passages therethrough serving as the female members of molds for making containers of edible material, a movable support in the base, a plurality of plungers held on the support and one of the plungers being reciprocably disposed through the lower end of each of the female members, the said 105 plungers being formed to provide movable bottoms for the female members when lowered so that their free ends will rest in the lower open ends of the female members, a carrier adapted to be raised and lowered to and from the top plate of the base, male 110 members on the carrier of an equal number to the female members, adapted to be guided inwardly and outwardly of the female members 115 when the carrier is accordingly moved, and the said male members being smaller in sizes than the interior of the female members for forming the interior of the containers, and means in the base, connected to the carrier and adapted to contact with the support of the plungers, whereby the carrier and the male members will be raised and lowered relative to the base for alternately inserting 120 and withdrawing the male members in and 125

out of the female members as well as synchronously reciprocating the plungers in the female members when the said means is operated, substantially as set forth and for the purpose specified.

3. In a machine of the character described, a hollow base having a stationary transverse top plate provided with a vertically disposed passage therethrough serving as the female member of a mold for making a container of edible material adapted to be baked, a movable support in the base, a plunger held on the support, and reciprocably disposed through the lower end of the female member, said plunger being formed to provide a movable bottom for the female member when lowered so that its free end rests in the lower open end of the female member, a carrier adapted to be raised and lowered to and from the top plate of the base, a male member on the carrier, adapted to be guided inwardly and outwardly of the female member when the carrier is accordingly moved, and the said male member being smaller in size than the interior of the female member for forming the interior of the container, means in the base, connected to the carrier and adapted to contact with the support of the plunger, whereby the carrier and the male member will be raised and lowered relative to the base for alternately inserting and withdrawing the male member in and out of the female member as well as synchronously reciprocating the plunger in the female member when the said means is operated, and heating means associated with the molds for baking the material of the container when molded, substantially as set forth.

4. In a machine of the character described, a hollow base having a stationary transverse top plate provided with a plurality of vertically disposed passages therethrough serving as the female members of a mold for making containers of edible material adapted to be baked, a movable support in the base, a plurality of plungers held on the support, and one of the plungers being reciprocably disposed through the lower end of each of the female members, the said plungers being formed to provide a movable bottom for the female members when lowered so that their free ends will rest in the lower open ends of the female members, a carrier adapted to be raised and lowered to and from the top plate of the base, male members on the carrier of an equal number to the female carriers, adapted to be guided inwardly and outwardly of the female members when the carrier is accordingly moved, and the said male members being smaller in size than the interior of the female members for forming the interior of the containers, means in the base, connected to the carrier and adapted to contact with the support of the plungers,

whereby the carrier and the male members will be raised and lowered relative to the base for alternately inserting and withdrawing the male members in and out of the female members as well as synchronously reciprocating the plungers in the female members when the said means is operated, and heating means associated with the molds for baking the material of the containers when molded, substantially as set forth.

5. In a machine of the character described, a hollow base having a stationary transverse top plate provided with a vertically disposed passage therethrough serving as the female member of a mold for making a flat-bottom container of edible material, a plunger reciprocably disposed through the lower end of the female member, said plunger being formed to provide a movable bottom for the female member when lowered so that its free end rests in the lower open end of the female member, a male member movably supported on the base, adapted to be guided inwardly and outwardly of the female member when accordingly moved, and the said male member being smaller in size than the interior of the female member for forming the interior of the container, and operative means on the base, connected to the male member, and adapted to contact with the plunger, whereby the male member will be raised and lowered relative to the base for being alternately inserted in and withdrawn from the female member as well as synchronously reciprocating the plunger in the female member when the said means is operated, substantially as set forth and for the purpose specified.

6. In a machine of the character described, a hollow base having a stationary transverse top plate provided with a plurality of vertically disposed passages therethrough serving as the female members of molds for making flat bottom containers of edible material, a plurality of plungers, one being reciprocably disposed through the lower end of each of the female members, the said plungers being formed to provide movable bottoms for the female members when lowered so that their free ends will rest in the lower open ends of the female members, male members of an equal number to the female members, movably supported on the base, adapted to be guided inwardly and outwardly of the female members when accordingly moved, and the said male members being smaller in size than the interior of the female members for forming the interior of the containers, and operative means on the base, connected to the male members, and adapted to contact with the plungers, whereby the male members will be raised and lowered relative to the base for being

alternately inserted in and withdrawn from the female members as well as synchronously reciprocating the plungers in the female members when the said means is operated, substantially as set forth and for the purpose specified.

7. In a machine of the character described, a hollow base having a stationary transverse top plate provided with a vertically disposed passage therethrough serving as the female member of a mold for making a flat bottom container of edible material adapted to be baked, a plunger reciprocably disposed through the lower end 10 of the female member, said plunger being formed to provide a movable bottom for the female member when lowered so that its free end will rest in the lower open end of the female member, a male member movably 15 supported on the base, adapted to be guided inwardly and outwardly of the female member when accordingly moved, and the said male member being smaller in size than the interior of the female member for forming 20 the interior of the container, operative means on the base, connected to the female member, and adapted to contact with the plunger, whereby the male member will be raised and lowered relative to the base for being alternately inserted in and withdrawn from 25 the female member as well as synchronously reciprocating the plunger in the female member when the said means is operated, and heating means associated with the molds 30 for baking the material of the container when molded, substantially as set forth.

8. In a machine of the character described, a hollow base having a stationary transverse top plate provided with a plurality of vertically disposed passages therethrough serving as the female members of a mold for making containers of edible material adapted to be baked, a plurality of plungers, one being reciprocably disposed 40 through the lower end of each of the female members, the said plungers being formed to provide movable bottoms for the female members when lowered so that their free ends will rest in the lower open ends of the 45 female members, male members of equal number to the female members, and adapted to be guided inwardly and outwardly of the female members when accordingly moved, and the said male members being smaller in 50 size than the interior of the female members for forming the interior of the containers, operative means on the base, connected to the female members, and adapted to contact with the plungers, whereby the 55 male members will be raised and lowered relative to the base for being alternately inserted in and withdrawn from the female members as well as synchronously reciprocating the plungers in the female members 60

when the said means is operated, and heating means associated with the molds for baking the material of the containers when molded substantially as set forth. 65

9. In a machine of the character described, a hollow base having a stationary transverse top plate provided with a vertically disposed passage therethrough serving as the female member of a mold for making a container of edible material, a movable support in the base, a plunger held 70 on the support, and reciprocably disposed through the lower end of the female member, said plunger being formed to provide a movable bottom for the female member when lowered so that its free end rests in the lower open end of the female member, a bracket movably supported on the base so as to be raised and lowered to and from the top plate of the base, a male member 75 on the bracket, adapted to be guided inwardly and outwardly of the female member when the bracket is accordingly moved, and the said male member being smaller in size than the interior of the female member for forming the interior of the container, and a manually operative lever in the base, connected to the bracket, and adapted to contact with the support of the plunger, whereby the bracket and the male member will be raised and lowered relative 80 to the base for alternately inserting and withdrawing the male member in and out of the female member as well as synchronously reciprocating the plunger in the female member when the said lever is operated, substantially as set forth and for the purpose specified. 85

10. In a machine of the character described, a hollow base having a stationary transverse top plate provided with a plurality of vertically disposed passages therethrough serving as the female members of molds for making containers of edible material, a movable support in the base, a plurality of plungers held on the support, one of the plungers being reciprocably disposed 90 through the lower end of each of the female members, the said plungers being formed to provide movable bottoms for the female members when lowered so that their free ends will rest in the lower open ends of the female members, a bracket movably supported on the base so as to be raised and lowered to and from the top plate of the base, male members on the bracket of an equal number to the female members, adapted to be guided inwardly and outwardly of the female members when the bracket is accordingly moved, and the said male members being smaller in sizes than the interior of the female members for forming the interior of the containers, and a manually operative lever in the base, con- 95 100 105 110 115 120 125

neeted to the bracket, and adapted to contact with the support of the plungers, whereby the bracket and the male members will be raised and lowered relative to the 5 base for alternately inserting and withdrawing the male members in and out of the female members as well as synchronously reciprocating the plungers in the female members when the said lever is operated, substantially as set forth and for the 10 purpose specified.

11. In a machine of the character described, a hollow base having a stationary transverse top plate provided with a vertically disposed passage therethrough serving as the female member of a mold for making a container of edible material adapted to be baked, a movable support in the base, a plunger held on the support, and 15 reciprocably disposed through the lower end of the female member, said plunger being formed to provide a movable bottom for the female member when lowered so that its free end rests in the lower open end of the 20 female member, a bracket movably supported in the base so as to be raised and lowered to and from the top plate of the base, a male member on the bracket, adapted to be guided inwardly and outwardly of the 25 female member when the bracket is accordingly moved, and the said member being smaller in size than the interior of the female member for forming the interior of the container, a manually operative lever 30 in the base, connected to the bracket, and adapted to contact with the support of the plunger, whereby the bracket and the male member will be raised and lowered relative to the base for alternately inserting 35 and withdrawing the male member in and out of the female member as well as synchronously reciprocating the plunger in the female member when the said means is operated, heating means associated with the 40 molds for baking the material of the container when molded, and means for regulating the degree of heat supplied to the molds, substantially as set forth.

12. In a machine of the character described, a hollow base having a stationary transverse top plate provided with a plurality of vertically disposed passages therethrough serving as the female members of a mold for making bakable containers of 55 edible material with flat bottoms, a movable support in the base, a plurality of plungers held on the support, and one of the plungers being reciprocably disposed through the lower end of each of the female members, 60 the said plungers being formed to provide movable bottoms for the female members when lowered so that their free ends will rest in the lower open ends of the female members, a bracket movably supported on

the base so as to be raised and lowered to 65 and from the top plate of the base, male members on the bracket of an equal number to the female members, adapted to be guided inwardly and outwardly of the female members when the bracket is accordingly moved, and the said male members being smaller in sizes than the interior of the female members, a manually operative lever in the base, connected to the bracket, and adapted to contact with the support of 70 the plungers, whereby the bracket and the male members will be raised and lowered relative to the base for alternately inserting and withdrawing the male members in and out of the female members as well as 75 synchronously reciprocating the plungers in the female members when the said lever is operated, an electric circuit with a plurality of resisting coils one arranged on each of the female members and one on each of the 80 male members for heating the molds to bake the containers when molded, and a rheostat in the circuit for permitting the supply of electricity to the resisting coils to be 85 regulated, substantially as set forth.

13. In a machine of the character described, a hollow base having a stationary transverse top plate provided with a vertically disposed passage therethrough serving as the female member of a mold for making 95 a container of edible material, a movable support in the base, a plunger held on the support, and reciprocably disposed through the lower end of the female member, said plunger being formed to provide a movable 100 bottom for the female member when lowered so that its free end rests in the lower open end of the female member, a carrier adapted to be raised and lowered to and from the top plate of the base, a male member on the carrier, adapted to be guided inwardly and outwardly of the female member when the carrier is accordingly moved, and the said male member being smaller in 105 size than the interior of the female member for forming the interior of the container, and means in the base, connected to the carrier and adapted to contact with the support of the plunger, whereby the carrier and the male member will be raised and lowered relative to the base for alternately inserting and withdrawing the male member in and out of the female member as well as synchronously reciprocating the plunger in the female member when the said means is operated, and a hopper adjustably supported on the base whereby suitable quantities of the material for making the container may be fed to the female member at intervals, substantially as set forth.

14. In a machine of the character described, a hollow base having a stationary transverse top plate provided with a plu-

- 5 rality of vertically disposed passages there-
through serving as the female members of
molds for making containers of edible mate-
rial, a movable support in the base, a plun-
ger held on the support, and
10 rality of plungers held on the support, and
one of the plungers being reciprocably dis-
posed through the lower end of each of the
female members, the said plungers being
formed to provide movable bottoms for the
15 female members when lowered so that their
free ends will rest in the lower open ends
of the female members, a carrier adapted to
be raised and lowered to and from the top
plate of the base, male members on the car-
rier of an equal number to the female mem-
bers, adapted to be guided inwardly and
outwardly of the female members when the
carrier is accordingly moved, and the said
20 male members being smaller in size than
the interior of the female members for
forming the interior of the containers, and
means in the base, connected to the carrier,
and adapted to contact with the support
25 of the plungers, whereby the carrier and the
male members will be raised and lowered
relative to the base for alternately inserting
and withdrawing the male members in and
out of the female members as well as syn-
30 chronously reciprocating the plungers in the
female members when the said means is op-
erated, and a hopper adjustably supported
on the base whereby suitable quantities of
the material for making the containers may
35 be fed to the female members at intervals,
substantially as set forth.
15. In a machine of the character de-
scribed, a hollow base having a stationary
transverse top plate provided with a verti-
cally disposed passage therethrough serving
40 as the female member of a mold for making
a container of edible material adapted to be
baked, a movable support in the base, a plun-
ger held on the support, and reciprocably
disposed through the lower end of the female
45 member, said plunger being formed to pro-
vide a movable bottom for the female mem-
ber when lowered so that its free end rests in
the lower open end of the female member, a
carrier adapted to be raised and lowered to
50 and from the top plate of the base, a male
member on the carrier, adapted to be guided
inwardly and outwardly of the female mem-
ber when the carrier is accordingly moved,
and the said male member being smaller in
55 size than the interior of the female member
for forming the interior of the container,
means in the base, connected to the carrier,
and adapted to contact with the support of
the plunger, whereby the carrier and the
- male member will be raised and lowered rela-
tive to the base for alternately inserting and
60 withdrawing the male member in and out of
the female member as well as synchronously
reciprocating the plunger in the female
member, when the said means is oper-
65 ated, and heating means associated with the
mold for baking the material of the con-
tainer when molded, and a hopper adjust-
ably supported on the base whereby suitable
70 quantities of the material for making the
container may be fed to the female member
at intervals, substantially as set forth.
16. In a machine of the character de-
scribed, a hollow base having a stationary
75 transverse top plate provided with a plu-
rality of vertically disposed passages there-
through serving as the female members of a
mold for making containers of edible mate-
rial adapted to be baked, a movable support
80 in the base, a plurality of plungers held on
the support, and one of the plungers being
reciprocably disposed through the lower end
of each of the female members, the said
plungers being formed to provide a movable
85 bottom for the female members when lowered
so that their free ends will rest in the lower
open ends of the female members, a carrier
adapted to be raised and lowered to and
from the top plate of the base, male mem-
90 bers on the carrier of an equal number to the
female members, adapted to be guided in-
wardly and outwardly of the female mem-
bers when the carrier is accordingly moved,
and the said male members being smaller
95 in size than the interior of the female mem-
bers for forming the interior of the con-
tainers, means in the base, connected to the
carrier and adapted to contact with the sup-
port of the plungers, whereby the carrier and
100 the male members will be raised and lowered
relative to the base for alternately inserting
and withdrawing the male members in and
out of the female members as well as syn-
chronously reciprocating the plungers in the
105 female members when the said means is oper-
ated, heating means associated with the
molds for baking the material of the con-
tainers when molded, and a hopper adjust-
ably supported on the base whereby suitable
110 quantities of the material for making the
containers may be fed to the female members
at intervals, substantially as set forth.

This specification signed and witnessed
this twenty-sixth day of March, A. D. 1915.

WILLIAM E. MOORE.
